VALVE

Perry S. Pine, Hoosick Falls, N. Y., assignor to
 Noble & Wood Machine Co., Hoosick Falls, N. Y.,
 a corporation of New York

Application September 3, 1947, Serial No. 771,855

2 Claims. (Cl. 251—10)

1

My present invention relates to valves, and more particularly to valves of the flap dump type and to means for facilitating the opening thereof.

Dump valves, particularly those of large size, i. e. twelve or more inches in diameter, such as are used in paper beaters, are for the most part quite difficult to open when the beater, pulper or stock chest is full of stock. This difficulty is due partly to the weight of stock over the valve, partly to the seal of the valve on its seat, and partly to the vacuum in the pipe line used for running off the stock in paper mills.

Where a dump valve of the sizes mentioned is held by only a very slight vacuum, it is difficult to "crack" the valve open, even without any head of stock whatever over the valve, and such difficulty is increased as the depth of the stock, and hence the weight of such stock on the valve, is increased. As a result operating shafts sometimes become broken and in general the extreme difficulty of opening these valves when the pipe lines from the beaters to the chest were emptying and when the beaters were full causes many delays in the mill.

In order to overcome these and other objections to the conventional dump valve, I have devised my present invention.

According to it, I provide near the inside edge of the valve a cam linkage for first tilting one edge of the valve to open the same. The thrust action on this linkage is greatly multiplied, due to its position as close as possible to the source of applied power. This increase of thrust and the resulting tilt on one edge of the valve, breaks the seal of the valve to its seat, and any vacuum, with the minimum of applied force. It also allows a certain amount of water and stock to enter the discharge passage before the center linkage comes to bear on the valve takes over the thrust, and opens the valve in the conventional manner.

The principal object of my invention is an improved dump valve and mechanism for facilitating the opening operation thereof.

Another object is an improved valve operating means for opening a dump valve by a combined tilting and lifting operation.

Other objects and novel features of the construction and operation of parts comprising my improved valve will appear as the description of my invention progresses.

In the accompanying drawing illustrating a preferred embodiment of my invention:

Fig. 1 is a vertical sectional side elevational view showing my novel valve and operating mechanism in closed position, and

Fig. 2 in vertical sectional side elevation of the upper portion of Fig. 1, showing the position of the parts after the preliminary tilting of the valve on its seat, and prior to the full opening of the valve.

Referring to the drawing, 10 designates the valve body, set into an opening formed in the bottom 11 (shown in dash lines) of a beater or other receptacle. The body 10 is threaded on its lower end at 12 to receive a flange 13 by means of which it may be attached to a discharge pipe or line. A passage 14 extends upwardly through the valve body 10 and at its upper end the material of the body is provided with an inset valve seat 15.

At one side of the body 10 and formed integral therewith is a chamber 16 which houses one end of an operating lever 17.

Associated with the valve seat 15, and seating thereon, as shown in Fig. 1, is the valve member 18. This valve member 18 has formed integral therewith on its under face one or more depending strengthening ribs 19, and also is provided with integral depending lugs 20 and 21. Lug 20 is in the center of the valve member and lug 21 lies adjacent to the edge of the valve member 18 nearest the chamber 16. At the lower end of lug 20 is a transverse shaft 22 and at the lower end of lug 21 is a shaft 23.

Rotatably mounted in suitable bearings in the material forming the chamber 16 is a shaft 24. One end of shaft 24 extends outwardly of said chamber, and has mounted on such extended end an operating lever 25. That portion of the shaft 24, within the chamber 16, is made square, as indicated at 26, and on this squared portion is mounted the outer end of operating lever 17.

Between its ends lever 17 is provided with an extension 27 rotatable on the shaft 23, and at its inner end said lever has an extension 28 provided with an elongated slot 29 engaging with and slidable on the shaft 22 mounted on the depending lug 20 at the center of the under face of the valve 18.

Assuming that the valve is closed, as shown in Fig. 1, and it is desired to open the same, the operation is as follows:

The operator pulls on the lever 25 to rotate shaft 24 in a clockwise direction. This moves the inner end 28 of the operating lever 17 upwardly over the shaft 22 until the shaft 22 rests in the lower end of the slot 29, as shown in Fig. 2. Simultaneously, the extension 27 of lever 17 which lies nearest the pivot shaft 24 and thus 55 acts with greatly multiplied force, tilts the edge

of the valve 18 off the seat 15, and thus breaks the seal of the valve on its seat, and allows the passage of a small amount of water and vapor to flow through the valve passage 14 and into the discharge passage or line.

Once the valve 18 is tilted off seat 15, continued movement of the lever 25 through the upward force exerted on the shaft 22 at the center of the valve by the extension 28 of lever 17 readily lifts and tilts the valve to its fully open position.

In actual practice, rotation of the shaft 24 through an angle of 45° will cause a rotative movement of the valve 18 on the shaft 22 through 60°.

I claim:

1. Apparatus for cracking and opening a dump valve in two steps wherein greater leverage will be available for the cracking step, comprising, a lever working arm extending transversely of the valve, a fulcrum for the lever adjacent to the margin of the valve, a first lug mounted on the valve adjacent to the lever working arm and adjacent to the margin of the valve nearest the lever fulcrum, the lever working arm being pivotally connected to the first lug, a second lug mounted substantially toward the center of the valve, a cross-pin mounted on said second lug, walls defining a slot in said lever working arm, said cross-pin slidably in said slot to permit free operation of the lever working arm through a limited arc but to engage the lug if the lever working arm is further operated, whereby initial operation of the lever brings force to bear upon the first lug with a short lever working arm to

tilt the valve, and further operation of the lever brings force to bear upon the second lug with a long lever working arm to open the valve.

2. Apparatus for cracking and opening a dump valve in two steps wherein greater leverage will be available for the cracking step, comprising, a lever arm extending transversely of the valve, a fulcrum for the lever arm adjacent to the margin of the valve, means pivotally connecting the lever arm to the valve at a point near the margin of the valve adjacent to the said fulcrum whereby operation of the lever will unseat the margin of the valve nearest the fulcrum, and means connecting the lever arm to the valve at a second point nearer the center thereof including a lug secured to said valve, a pin on said lug, a slot in said lever arm and said pin riding in said slot whereby to permit a limited axial component of motion of the lever, but to engage the lever arm and open the valve after sufficient motion of the lever arm has taken place to crack the valve.
